TRICK DEVICE

Kenneth S. Franke, New York, N. Y.

Application February 3, 1940, Serial No. 317,045

6 Claims. (C.I. 272-8)

This invention relates to trick devices such as are used by magicians for presenting illusions and more particularly to a device by means of which a coin-like object can be made to vanish

5 mysteriously. The primary object of the invention is to provide a simple device which can be used for the amusement and mystification of those viewing a demonstration and by means of which the coin-like object can apparently be made to disappear while the device is being manipulated in close proximity to the viewers.

10 Another object is to provide a device of this type which can be manipulated by a person unskilled in the art of magic while the secret of the performance is easily concealed.

15 In accordance with the invention, an object which may resemble a coin and preferably having the appearance of being formed of a non-magnetic material such as copper or brass, is placed on a table or other support or in a suitable receptacle and a block member having the outward appearance of a solid homogeneous mass of wood or the like is placed over and in close proximity to the object. When the block is removed the coin-like object has mysteriously disappeared. The secret resides in the concealment of a small magnet in the block near one surface thereof and in the provision of some magnetic

20 material which may be concealed in or under the coin-like object. The magnet attracts the object because of the magnetic material therein and causes it to adhere to the surface of the block. After removing the block the performer

25 can easily slip the object therefrom and conceal it in his hand or pocket, unobserved by those viewing the performance.

30 For a better understanding of the invention, reference may be had to the accompanying drawings in which:

Figure 1 is a perspective view illustrating one embodiment of the invention;

Figure 2 is a plan view of the block showing the magnet concealed therein;

Figure 3 is an elevation of one edge of the block;

Figure 4 is a longitudinal section taken on line 4-4 of Figure 2; while

Figure 5 is a front perspective view showing the block after it has been removed from the receptacle with the coin-like object adhering to the lower side of the block.

Referring to the drawing, a receptacle 10 having an opening or indentation 12 in one side thereof is adapted to hold an object 14 which

may be a plain disc or token or which may resemble a coin in outward appearance. The receptacle member 10 is formed of any non-magnetic material such as wood, pressed paper or a suitable plastic. The opening 12 may, if desired, be lined with felt or any other such material for the purpose of improving the appearance. An upper or block member 16 is also formed of non-magnetic material similar to that of the member 10 and may, as shown, be of the same general shape as the lower or receptacle member. The block 16 is provided with upper and lower substantially parallel surfaces 18 and 20 respectively, and a hole 22 is formed in the block extending from one edge to a point beyond the center of the block. As will be observed with reference to Figures 3 and 4, the hole 22 is formed nearer to the surface 20 than to the surface 18 for purposes which will be described hereinafter. A magnet 24 is disposed in the hole 22 at substantially the center of the block, and the remainder of the hole 22 is preferably filled with a plug 26 of non-magnetic material similar to the material from which the block 16 is formed. The outer end of the hole 22 and plug 26 may be covered with a suitable label 28 in order to conceal the fact that a hole has been drilled in the block and that the block comprises anything but a solid homogeneous mass.

If desired, the object 14 may be formed entirely of magnetic material such as iron and, in fact, this object may comprise merely a small iron disc such as a washer. However, it is preferred that the object 14 present the outward appearance of being formed of a non-magnetic material such as copper or brass in which case the lower side of the object may have a small amount of iron embodied therein or secured thereto as in the form of a second disc. In this case, it is merely desirable that a person on viewing the object 14, either within the opening 12 of the receptacle 10 or when placed on a table or other support, receive the impression that the object is formed of a material which could not be attracted by a magnet.

In operation, the object 14 is placed in the opening 12 of the receptacle 10 and the block member 16 is then placed upon the receptacle 10 with the surface 20 of the block resting against the receptacle. The object 14 will be attracted by the magnet 24 and will adhere to the surface 20 of the block 16 so that when the block is lifted and removed, as is shown in Figure 5, the object 12 will also be removed therewith from the receptacle. After the performer removes

the block 16 he can easily slip the coin-like object 14 from the under surface of the block and can conceal it in his hand or pocket after which the block, as well as the receptacle, may be passed around for examination by the viewers. The effect, therefore, is that in some mysterious manner the coin-like object 14 has disappeared while being covered by the block 16.

When the block 16 is placed on the receptacle 10 with the surface 18 downward or adjacent the receptacle, the magnet 24 will not be sufficiently powerful to attract the object 14 so as to cause it to adhere to the surface 18, since the magnet is so disposed in the block that there is a greater thickness of the non-magnetic material of the block between the magnet and the surface 18 than between the magnet and the surface 20. By means of this feature additional effects can be produced. For instance, after the performer 20 has caused the coin-like object 14 seemingly to disappear, he again produces it or a similar object and places it once more in the opening 12 of the receptacle or on a suitable support. The performer then holding the block 16 in his hand, 25 turns it over while unobserved by the audience and then places the block 16 so that the side 18 will be over and adjacent the object 14. He then either hands the entire device to one of the onlookers or, in the case where the object 14 is 30 placed upon a table without the use of the receptacle, he merely requests the onlooker to make the object disappear. Since the surface 18 of the block is now adjacent the object, the object will not adhere to the block and the onlooker will be 35 unable to make the object disappear. The performer will then again take the block 16 and while unobserved by the onlookers reverses it so that the surface 20 is again downward. He then places the block over the object whereupon the latter will adhere to the block and seemingly disappear to the particular amazement of the onlooker who has just previously endeavored to do the same trick without result.

As has been indicated in the foregoing description, although it is preferred that the receptacle member 10 be used, it is understood that this member is not necessary, since the object 14 can be laid upon and caused to disappear from any suitable surface such as the top of a table. 50 Again, the block 16 may be formed in various other shapes and, as stated hereinbefore, may be made of any suitable non-magnetic material such as wood, cardboard, a plastic or the like.

Obviously many other modifications and variations of the invention as hereinbefore set forth may be made without departing from the spirit and scope thereof, and therefore only such limitations should be imposed as are indicated by the appended claims.

60 I claim:

1. A trick device comprising a block member having the outward appearance of a substantially unitary mass and having upper and lower surfaces, a coin-like object formed at least partially of magnetic material and means for causing said object to adhere to the under surface of said member comprising a magnet concealed in said block member in closer proximity to the under surface than to the upper surface.

70 2. A trick device comprising a block-like cover

member, a coin-like object being formed on its normally upper side of a non-magnetic material and on its lower side of magnetic material, and a magnet concealed within said member, whereby, when said member is placed over and in close proximity to the non-magnetic side of said object, the object will adhere to the lower side of said member so that the object will be removed from its original position when the cover member is removed, thus providing the illusion that the object has disappeared.

3. A device for presenting the illusion of causing a coin-like object to disappear comprising a member having the outward appearance of a solid homogeneous mass, and a magnet concealed in said member closer to one side of said member than to the other side, said object being formed at least partially of magnetic material and said magnet being adapted to attract and cause said object to adhere to said member when the side of said member nearer the magnet is placed in close proximity to said object, so that when said member is subsequently removed, the object will be removed therewith, while when the side of said member away from said magnet is placed in close proximity to said object there will be insufficient magnetic attraction to cause the object to adhere to the member.

4. A trick device comprising a block-like member having the outward appearance of a unitary mass, and provided with substantially parallel upper and lower sides, a magnet embedded and concealed in said member but closer to one of said sides than to the other, and a coin-like object formed at least partially of magnetic material and adapted to be covered by said member whereby when said member is placed with one of said sides over and in close proximity to said object the object will either adhere or not adhere to the member depending on which of said sides is closer to said object.

5. A trick device comprising a member having the outward appearance of a unitary, homogeneous mass, a magnet concealed within said member, and an object adapted to be attracted to and to adhere to one surface of said member comprising a relatively thin, wafer-like element formed at least partly of magnetic material, the arrangement being such that when said member is placed in close proximity to and over said object, the object will adhere to the lower side of the member whereupon, when the member is lifted and removed the illusion will be presented that the object has disappeared from its original resting place while covered by said member.

6. A device for presenting an illusion comprising a lower member having an indentation in one side adapted to hold a coin-like object or token at least a portion of which is formed of magnetic material, an upper member having the appearance of a solid block, and a magnet concealed within said upper member, said upper member being adapted to rest upon said lower member over said indentation containing said token and the magnet being adapted, when the upper member is lifted, to lift and remove said token from the lower member to give the effect that the token disappeared while the lower member was covered by the upper member.

KENNETH S. FRANKE. 70
